UNITED STATES PATENT OFFICE

WENDELL L. CARLSON AND DONALD WILSON, OF SCHENECTADY, NEW YORK, ASSIGNEES
TO GENERAL ELECTRIC COMPANY, A CORPORATION OF NEW YORK

ELECTRICAL SIGNAL AMPLIFYING APPARATUS

Application filed July 6, 1928. Serial No. 290,803.

Our invention relates to electrical signal amplifying apparatus embodying electric discharge devices and more particularly to an apparatus of this character in which the 5 anode, cathode and grid bias voltages for such electric discharge devices are taken wholly or in part from a common supply means. With improved coupling means in such apparatus as, for example, improved 10 audio frequency transformers and resistance coupling devices in a sound amplifying apparatus, and a common source of energy for the various coupled circuits and electric discharge devices therein, a varying current of 15 relatively low frequency often builds up in the output circuit and with a sound reproducer therein causes a persistent fluttering or "motor boating" noise in the latter. This may be caused by poor voltage regulation at 20 the supply terminals, acoustic feedback, overloading the output tube, an undesirable coupling between the various circuits through the common supply means, or a combination of these causes. 25 Poor regulation, that is, the inability to hold substantially constant supply voltage with varying load is caused by high internal resistance at some point in the supply circuit. This is a salient characteristic of 30 the usual rectified alternating current source of energy now commonly used with apparatus embodying electric discharge devices. The resistance may become a common coupling means for a plurality of circuits and 35 in an amplifier circuit for sound amplification and reproduction, for example, may become the source of troublesome audible fluttering or "motor boating" as above mentioned. In other apparatus of this character, a fluttering or varying output, while not necessarily 40 audible, is nevertheless highly undesirable. It is therefore the object of our invention to provide an improved circuit arrangement for supplying energy from a common 45 means having relatively poor voltage regulation to a plurality of electric discharge devices in an electrical amplifying apparatus without obtaining an undesirable fluctuation in the output circuit of such apparatus.

Our invention will be better understood from the following description when considered in connection with the accompanying drawing, and its scope will be pointed out in the appended claims.

55

In the drawing, the single figure is a wiring diagram of an apparatus embodying our invention. By way of example, and not in any way as indicating a limitation in the application of our invention, this is a wiring diagram of a radio receiving set provided with a plurality of receiving and amplifying electric discharge devices 5 of the vacuum tube type having cathode and control grid connection with a tapped cathode and grid voltage supply resistor 6, and anode connection with high and low voltage supply leads 7 and 8. The usual apparatus in the anode and grid circuits of these devices is not shown as it does not concern the invention and the diagram is greatly simplified and more readily understood by its omission.

60

65

70

Anode supply leads 7 and 8, together with an anode return lead 9, connect with a tapped plate supply or anode resistor 10. Lead 9 in effect connects resistors 6 and 10 in series and they are then connected in this relation with suitable high voltage direct current supply terminals 11 and 12, the polarity of 75 which is indicated in the drawing. This represents a known voltage divider resistor arrangement in an apparatus of this character for obtaining anode, cathode and bias voltages from a common high voltage direct current source.

80

85

90

95

In the present example, the high voltage direct current is obtained from rectified and filtered alternating current through a common and well known rectifier and filter apparatus represented by transformer 13, rectifiers 14 and filter choke and capacities 15 and 16 respectively.

100

Alternating current of the usual commercial voltage and frequency is supplied from lines 17 and after being stepped up by the transformer is rectified at 14 and passed through filter 15—16 to the supply terminals 11 and 12. The voltage regulation at terminals 11 and 12 depends upon the load

drawn by the apparatus connected therewith because of the inherently poor regulation caused for the most part by the internal resistance of rectifiers 14 and of the filter choke 15, and this supply means may be taken as representing any supply means of this character.

If now, as is customary, the anode or plate supply current for an output device, such as a power tube 18, is taken through resistor 6 and the filaments connected therewith, then an undesirable fluttering or low frequency variation in the output anode current often results because of poor regulation at supply terminals 11 and 12 with the varying load taken by the apparatus connected therewith and because plate current variations of the power or output tube 18 cause fluctuations of the filament emission of amplifier tubes 5 which in turn cause voltage fluctuations to be transmitted to the power tube either directly by the audio amplifier or by modulation of the carrier wave being received. This is carried through to the power tube 18, which in the present example is coupled with the amplifying and receiving apparatus by a suitable transformer or other coupling device 19, the secondary of which is connected with the grid circuit 20 of the power tube.

These variations are then transmitted to apparatus connected with an output circuit 21 which in the present example is connected through a suitable output transformer 22 with the output or anode circuit 23 of the power tube. When as shown, the output circuit supplies a sound producer or loud speaker indicated at 24, the fluttering or varying output current in anode circuit 23 is reproduced by the loud speaker.

In accordance with our invention, however, we arrange the anode circuit of the output or power device 18 in such a manner that the anode or plate current therefor does not flow through either the anode or the filament circuits of the preceding amplifying devices 5, that is, in the present example, the anode circuit of tube 18 is so arranged that it does not include resistor 6 and the filament circuits of the preceding tubes 5.

In carrying out this improved circuit arrangement, the high potential side of the output anode circuit 23 connects with the high potential supply terminal 12 through a supply lead 25 while a cathode return lead 26 for this circuit connects with the low potential supply terminal 11. The grid circuit 20 returns to the same point through a return lead 27, and a suitable resistor 28 in lead 26 bypassed by a capacity 29, serves to effect the proper bias on the grid of the power or output device 18. The cathode of this device is heated from a separate source which in the present example is a mid-tapped low voltage secondary 30 on the power supply transformer 13.

Interposed between the high potential supply terminal 12 and the voltage divider resistor, in such a manner that it is included in the voltage divider circuit, is an impedance or choke coil 31 which may be of any suitable construction having a relatively low resistance and a relatively high impedance to current fluctuations. This choke coil is preferably by-passed on its low potential side to the low potential supply terminal 11 by a condenser or capacity 32 of relatively high value corresponding to those used in the filter at 16, and together with the choke coil provides a low frequency filter for the voltage divider circuit 10—9—6 and the anode and cathode supply circuits connected therewith. The use of a high impedance interposed in the voltage divider circuit in series with the voltage divider resistance tends to reduce the hum in connected apparatus, such as the reproducer 24, resulting from such current fluctuations.

The choke coil or impedance and series connected voltage divider resistance for the anode and plate may be considered to form an independent shunt circuit across the supply terminals 11 and 12. Viewed in another aspect the plate circuit of power or output tube 18 is connected between the choke coils 15 and 31 whereby the output tube connection is separated from the voltage divider resistor by the latter choke coil.

With rectified alternating current as the power source it is desirable to shunt the filament and grid bias portion of the resistor for the preceding tubes, that is, resistor 6, with a by-pass capacity as indicated at 33.

With the above described circuit arrangement, it will be seen that in an apparatus having a common supply or voltage divider resistor, such as resistors 10 and 6 these resistors are connected across the supply terminals, while the output or anode circuit of the power tube connects directly with the supply terminals and not into or through these resistors or any part thereof. Thus none of the output anode current flows in the voltage divider resistor or in the circuits with which it is connected, that is, in either the anode or the cathode circuits of the preceding electric discharge devices of the amplifying apparatus.

This circuit arrangement has been found to eliminate the fluttering characteristic in and has resulted in satisfactory and stable operation of apparatus of the character described permitting the use of a common supply source for the anode circuit of an output tube and the filament and plate supply of preceding tubes, without being affected by the normal regulation of such supply source.

What we claim as new and desire to secure by Letters Patent of the United States, is:

1. In an amplifying apparatus, a pair of high voltage supply terminals, a voltage di-

vider resistor connected across said terminals, a cathode supply circuit connected in shunt with at least a portion of said resistor, and an output electric discharge device having an anode circuit connected

5 with said supply terminals independently of said resistor whereby the anode current for said device flows directly from said terminals without passing through said resistor and the cathode supply circuit.

10 2. In an amplifying apparatus having a pair of high voltage supply terminals, the combination of a voltage divider resistor connected across said terminals, a cathode supply circuit connected in shunt with at least a portion of said resistor, an output electric discharge device having an anode circuit connected with said supply terminals independently of said resistor, and means providing a relatively high impedance to current fluctuations connected between said resistor and one of said terminals.

15 3. In an amplifying apparatus embodying electric discharge devices and having high voltage supply terminals, the combination of an output circuit connected directly with said terminals, a plurality of anode circuits, a cathode heating circuit, and voltage divider means through which said anode and cathode heating circuits are connected with said terminals independently of said output circuit.

20 4. In an amplifying apparatus embodying a plurality of electric discharge devices, the combination with common high voltage supply terminals for said devices, of an output circuit connected directly with said terminals, a plurality of anode circuits, an anode supply resistor through which said anode circuits are connected with said terminals, a cathode supply resistor in series with the anode supply resistor at the low potential end thereof, and a plurality of cathodes connected with said cathode supply resistor.

25 5. In an amplifying apparatus embodying electric discharge devices, the combination of an anode supply resistor, a cathode supply resistor, said resistors being connected in series, a high potential supply terminal with which the first named resistor is connected, a low potential supply terminal with which the second named resistor is connected, an output anode circuit having a supply lead connected with the high potential supply terminal and a cathode return lead connected with the low potential supply terminal whereby said circuit is connected with said terminals in parallel with said series connected resistors.

30 6. In an amplifying apparatus embodying electric discharge devices and having high voltage supply terminals, the combination of an output anode circuit connected directly with said terminals, a plurality of additional anode circuits, a cathode heating circuit, voltage divider means through which said anode and cathode heating circuits are connected

with said terminals independently of said output circuit, and an impedance means connected between said output anode circuit and said voltage divider means in circuit with the latter.

7. The combination of a pair of interconnected electric discharge devices, a power supply circuit, and a filter means provided with end terminals connected respectively to said circuit and to the output circuit of one of said devices and with an intermediate terminal connected to the output circuit of the other of said devices whereby the output circuits of said devices are isolated from each other, said filter means including an impedance element connected in series with said output circuit of said one of said discharge devices, said impedance element being characterized by relatively low resistance to direct current and relatively high impedance to the alternating components of current in said power supply circuit.

8. In an apparatus embodying electric discharge devices, the combination of an output device therefor, having a grid circuit, a second device having an anode circuit coupled with said grid circuit, means providing a supply circuit in connection with said last named device for supplying electrical energy thereto, a filter means in said circuit for smoothing the flow of energy therethrough, and an output anode circuit for said output device connected with said filter intermediate its ends for receiving energy therefrom, whereby said anode circuit is isolated from said supply circuit and hum effects in the output of said output device are obviated.

In witness whereof, we have hereunto set our hands this 30th day of June 1928.

WENDELL L. CARLSON. 105
DONALD WILSON.
